UNITED STATES PATENT OFFICE

OTHO V. KEAN, OF PROVIDENCE, RHODE ISLAND

SCRUBBER

Application filed December 8, 1927. Serial No. 238,499.

The present invention relates particularly to that type of scrubbers which are formed wholly or in part of an abrasive material having a plurality of angular metal surfaces 5 adapted to readily cut or wear away material which adheres to metal or glass containers, dishes or cooking utensils thereby making it possible to more quickly and easily remove adhering substances and facilitating 10 the cleansing of such articles.

One object of the present invention is the provision of an improved device of this character which possesses a high degree of flexibility and which is consequently capable of 15 adapting itself to the inequalities of the utensil to be washed and thus make contact with all parts thereof to remove foreign matter therefrom.

Another object of the invention is the provision of a device of this character which may have a core containing abrasive material whereby the abrasive properties of the structure are not destroyed upon the wearing through of parts of the cover portion but continue to exist so long as a portion of the core 25 remains unconsumed.

A further object of the invention is the provision of a device of this character having a flexible abrasive portion adapted to enter 30 constricted spaces in a surface to be cleaned, thereby increasing the efficiency of the scrubber.

Additional objects of the invention will be apparent by reference to the annexed specification taken in connection with the drawings, which latter illustrate one practical embodiment of the invention and in which:—

Fig. 1 is an elevational view of a braided wire fabric material, a portion of which is 40 expanded as by drawing the same over a mandrel or former.

Fig. 2 is an elevational view illustrating one step in the formation of the improved scrubber illustrating the insertion of a metallic core within the tubular wire mesh material.

Fig. 3 is a top plan view of the structure in partially completed condition showing the manner of positioning the core in the tubular wire mesh cover.

Fig. 4 is a vertical sectional view through

the scrubber in its completed form, illustrating diagrammatically the position of the various parts, and

Fig. 5 is an elevational view of the completed article.

Referring to the accompanying drawings wherein the same reference characters designate like parts throughout the several views; 1 designates a flat braided wire mesh formed of angular wire threads 2. The braid may be 55 formed in different ways and may of course be prepared by weaving, braiding, linking or otherwise connecting together angular metal threads or strands to form a tubular metal fabric having a plurality of abrasive 60 edges such as are, in the embodiment illustrated herewith, designated by the numeral 3. In the method of forming the abrasive material as illustrated herewith, angular wire threads 2 are braided together to form an initially flat braid 1 which is of tubular form 65 and capable of being expanded to separate the strands or threads 2 from each other, as by passing the tubular braid over a mandrel or former 4 as indicated in Fig. 1 of the drawings. As the tubular braid is passed over the former 4 the threads 2 are separated from 70 each other and in practice such threads are twisted or tilted slightly from their original position so that the edges 3 thereof are exposed to form, as it were, cutting edges for 75 abrading or cleaning metal, glass or other surfaces.

In the formation of the scrubber a section 6 of such expanded tubular wire mesh fabric 85 may be sleeved over a hollow tube 5, as shown in Fig. 2. A portion of the tubular wire mesh fabric sleeved over the tube 5 in Fig. 2 is shown as lying flatly against the outer surface of the tube as indicated at 7, while a portion thereof is shown as compressed longitudinally of the tube as indicated at 8 to form 90 surface corrugation in the tubular fabric. The sleeve 6 is compressed longitudinally 95 throughout its entire length while in position upon the tube 5, the portion 7 being shown lying flatly upon the surface of the tube to illustrate the position of the fabric when first sleeved upon the tube and before it is compressed longitudinally as above described.

This longitudinal compression of the sleeve section 6 not only forms external corrugations therein thus increasing the body or cross sectional bulk of the sleeve but also tends to increase the diameter of the braided tubular section.

A core 9 formed wholly or partially of a suitable abrasive material such as woven, braided, knitted or linked metal 10 mesh work, or of abrasive metal threads or strands such as those which are produced as waste in turning or planing metal parts, is inserted within one end of the tube 5 where it is available for withdrawal 15 with the compressed metal sleeve 8 in such a manner as to lie within the sleeve after the withdrawal of the parts from the tube 5. In the present instance the core 9 is shown as made from a section of tubular wire mesh 20 fabric similar to that which is sleeved over the tube 5. The core 9 being preferably compressed longitudinally and curved transversely to make it more compact. It will, of course, be understood that any desired number 25 of sections of wire mesh fabric may be employed in lieu of the single layer illustrated in the drawings.

A wire 10, of less length than the core 9 may be inserted within the tube 5 adjacent to 30 the core for a purpose which will be more fully described hereinafter.

Upon removal of the sleeve 6, core 9 and wire 10 from the tube 5 these parts assume a position substantially as shown in dotted 35 lines in Fig. 3 with the core 9 and wire 10 lying within the sleeve 6 which is compressed longitudinally of the core to form surface corrugations 11 therein. The core 9 and sleeve 6 are both compressed longitudinally 40 to permit the ends of the wire 10 to be brought together and secured as shown at 12. The ends 13 of the core 9 are then brought together and secured to each other in any suitable manner as by stitching or linking with a wire or 45 cord as indicated at 14. The free ends of the sleeve 6 are then brought together and secured to each other by stitching or in any other suitable manner. In this way the wire 10 tends to retain the core 9 and sleeve 6 in 50 their compressed state and prevents undue expansion of those parts longitudinally while in use.

After connecting the ends of the core 9 and sleeve 6 the scrubber assumes the form of an 55 annulus, and the annulus may then be shaped, by compressing one side into the form shown in Figs. 4 and 5, wherein the parts are disposed substantially as shown in Fig. 4 with the core 9 located adjacent to the central part 60 of the sleeve, the wire 10 holding the parts against expansion, and the lower flaring edge 15 of the sleeve projecting outwardly and away from the main portion of the core whereby the edge 15 is possessed of great flex- 65 ibility and thus adapted to be pressed into

constricted portions of the surfaces to be scrubbed or to conform readily with irregular surfaces which it may be desired to clean. It will be noted that the scrubber is compressed into the form of a truncated cone 70 whereby the smaller top portion may be readily grasped by the hand and the broader base portion utilized for scrubbing a surface to be cleaned. The wire 10 has the ends thereof connected together at such a point as to hold 75 the core and sleeve against undue expansion while permitting sufficient expansion or movement of the core and sleeve relative to the wire as to enable the parts of the core and sleeve to move to a limited extent and flex 80 sufficiently for efficient operation.

Thus, among others, the several objects of the invention are achieved. It will be understood, however, that numerous changes in construction and rearrangement of the parts 85 might be resorted to without in the slightest departing from the spirit of the invention as defined in the claims.

What I claim is:

1. A scrubber comprising an annular body, 90 a core formed of abrasive material, said core being disposed over said body, and a separate tubular wire mesh disposed over the core, said mesh being of a length greater than the core and being completely sleeved thereon 95 whereby to form surface corrugations in said mesh.

2. A scrubber comprising a core of reticulated tubular wire mesh fabric, and the length of said covering being greater than that of the 100 core and the former being completely sleeved upon the latter whereby surface corrugations are formed in said covering.

3. A scouring device comprising an abrasive flexible ring-shaped hollow covering disposed in the form of an axially hollow truncated cone having an outer edge portion, and a core within said covering and spaced from the outer edge of said cone.

In testimony whereof I have affixed my 110 signature.

OTHO V. KEAN.
